UNITED STATES PATENT OFFICE.

ROBERT A. BLUME, OF SEATTLE, WASHINGTON, ASSIGNOR TO VALVELESS ENGINE CORPORATION, OF SEATTLE, WASHINGTON, A CORPORATION OF WASHINGTON.

INTERNAL-COMBUSTION ENGINE.

1,154,366.

Specification of Letters Patent. Patented Sept. 21, 1915.

Application filed July 28, 1914. Serial No. 853,574.

To all whom it may concern:

Be it known that I, ROBERT A. BLUME, citizen of the United States, residing at Seattle, in the county of King and State of Washington, have invented a certain new and useful Improvement in Internal-Combustion Engines, of which the following is a specification.

My invention relates to improvements in 10 rotary engines of the internal combustion type in which a plurality of cylinders are secured to a crank case and adapted to revolve around a fixed shaft, and the object of my improvement is to provide an engine 15 adapted to run at a high speed with a minimum amount of vibration, and which shall embody efficient means for introducing successive charges of explosive mixture into each cylinder of such engine at proper instants of time. I accomplish this object by 20 devices illustrated in the accompanying drawings in which—

Figure 1 is a view in end elevation of an engine embodying my invention certain 25 parts being shown in cross-section for the purpose of more clearly illustrating the same; Fig. 2 is a view in cross-section on broken line A, A of Fig. 1, certain parts being shown in elevation, and Fig. 3 is a 30 view in cross-section of a detail of my invention.

Referring to the drawings, throughout which like reference numerals indicate like parts, 5 is a hexagonally shaped crank case 35 and 6 is a crank shaft that may be fixedly secured to any rigid support (not shown) and may extend through the crank case 5 as more clearly shown in Fig. 2.

Secured upon alternate faces of the hexagonally shaped crank case 5 are engine cylinders 7 and disposed between each of adjacent ones of said engine cylinders 7 is a pump cylinder 8, the pump cylinders 8 being arranged in a plane slightly to one 40 side of the plane in which the engine cylinders 7 are arranged, as more clearly shown in Fig. 2, whereby they may more easily be connected with the crank shaft 6.

The engine cylinders 7 and pump cylinders 8 are provided respectively with base flanges 9 and 10 by which such cylinders 7 and 8 may be bolted by bolts 11 to the ends 12 and 13 of the crank case 5, the bolts 11 serving to bind the crank case 5, the ends 55 12 and 13 and the cylinders 7 and 8 to-

gether. The ends 12 and 13 are provided with bearing boxes 14 and 15 through which the shaft 6 may extend.

The shaft 6 is provided with a crank pin 16 to which are secured connecting rods 17 60 that extend to, and are connected by, wrist pins 18 with pistons 19 in the engine cylinders 7 and such shaft 6 is further provided at a point near the crank pin 16 with another crank pin 20 that is disposed in a different radial plane and which is adapted to have secured thereto connecting rods 21 that are articulated by wrist pins 22 with pistons 23 that are disposed in the pump cylinders 8. The connection between the connecting rods 17 and the crank pin 16 is formed by permitting the inner flanged ends 24 of such connecting rods 17 to rest upon a bushing 25 that surrounds the crank pin 16 and by securing such flanged ends 24 70 in their proper position by rings 26 and 27 that slip over the flanges on such ends 24 and are secured by bolts 28, as more clearly shown in Fig. 2, the connection between the crank pin 20 and the connecting rods 22 being formed in a similar manner by securing the inner flanged ends of the connecting rods 22 to the crank pin 20 by rings 29 and 30 that are secured together by bolts 31.

The engine cylinders 7 are each provided 85 with exhaust ports 32 and with inlet ports 33 which inlet ports are connected with the pump cylinders 8 by passageways 34 whereby explosive mixtures may pass from the pump cylinders 8 into the engine cylinders 90 7, and such pump cylinders 8 are each connected by ports 35 and passageways 36 with an annular gas chamber 37 which is connected by a passageway 38 with a carbureter 39 of any ordinary form, within which carbureter 39 a proper explosive mixture of 95 gas and air for the cylinders 7, may be produced.

The pistons 19 are provided on their top ends with deflectors 40, more clearly shown in Fig. 1, and the engine cylinders 7 are each provided near their top ends with a spark plug 41 which may be adapted by any well known timing means to deliver a spark 100 into its cylinder at proper instants of time 105 to cause an explosion of gases whose expansion serves to operate the engine.

The pistons 23 in each of the pump cylinders are hollow, as shown in Fig. 1, and are each formed with a diagonally extending 110

partition 42 that divides such piston into two parts to guide the flow of gases therein, the pistons 23 each being provided near its inner end with a port 43 that is adapted 5 when such piston 23 is at the outermost position in its stroke, as shown in Fig. 1, to register with a port 44 in the side of the cylinder 8, which communicates with the passageway 34, whereby gases may flow 10 from the space above the wall 42 of the piston 22 into the space above the piston 19 in the cylinder 7.

A member 45, which forms the outer wall of the annular gas chamber 37, is secured to 15 the end 13 of the crank case and the outer end of such member 45 is adapted snugly to fit over and turn upon an annular bearing surface 46 provided on the inner end of a member 47 within which is formed the passageway 38 that leads to the carbureter thus forming a tight bearing through which air may not pass, the member 45 rotating and the member 47 remaining fixed.

The operation of my engine may be described as follows: The various parts are assembled, as shown in Figs. 1 and 2, and the shaft 6 is secured to any suitable support as to the frame of a machine, the carbureter 39 being connected with a suitable supply of 25 gasoline; the cylinders and crank case are then turned over by any suitable means, as by hand, until a charge of gas from the carbureter is drawn into one of the cylinders 7 and is ignited at the point of high compression 30 by a spark from a spark plug 41 to explode within the cylinder, thus to revolve the cylinders together with the crank case about the crank shaft 6 in a well known manner, explosions following in proper succession 35 in the other cylinders. In the engine, as shown in Fig. 1, when a pump cylinder 8 is in a position substantially opposite to the position of the cylinders 7 shown in cross-section, the piston 23 will be withdrawn 40 to the innermost limit of its stroke, as shown in Fig. 3, and will cause a charge of explosive mixture from the carbureter 39 to be drawn into such cylinder above the piston 23. As the revolution of the crank case continues in a clockwise direction the piston 23 will move upwardly until it reaches the position shown in cross-section 45 in Fig. 1, and until the port 43 registers with the port 44, to permit the charge of compressed explosive mixture above the piston 23 to flow outwardly into the then exhausting engine cylinder 7, the exhaust ports of which cylinder 7 are adapted to be closed at the proper point when such cylinder 50 has been properly scavenged of burned gases and before any of the fresh charge has passed outwardly therethrough. As the crank case and cylinders move around in a clockwise direction from the position shown 55 in Fig. 1, the piston 19 in the cylinder 7,

shown in cross-section, moves upwardly and compresses the charge in the cylinder 7 and when such cylinder 7 has reached a point in its revolution approximately opposite to the point shown in Fig. 1, a suitably timed spark is produced in such cylinder by the spark plug 41 to explode the charge therein to cause the pressure of expanding gases to do work to revolve the cylinder during the remainder of the revolution of such cylinder. 75

A belt pulley 48 may be secured to the end plate 12 and may be connected by a belt 49 with any suitable device to which power is to be communicated.

Obviously any desired number of cylinders may be provided on an engine constructed in accordance with my invention and numerous other changes may be made without departing from the spirit of my invention or sacrificing any of its advantages. 85

What I claim is:

1. In an engine of the class described, the combination with a crank case, of a plurality of engine cylinders secured to said crank case, pump cylinders each secured to said crank case in a position between adjacent ones of said engine cylinders, oppositely disposed inlet and exhaust ports in the engine and pump cylinders, passageways connecting the exhaust ports of the pump cylinders to the inlet ports of the engine cylinders, a carbureter connected with said crank case by suitable means to form a gas chamber, pipes connecting said pump cylinders with said gas chamber whereby gas may be drawn into said pump cylinder inlet ports, pistons provided in said engine cylinders, a fixed crank shaft, and connecting rods articulating said pistons with said crank shaft whereby explosions within said cylinders may operate to move said pistons to rotate said crank case together with said cylinders. 95

2. In an engine of the class described, the combination with a rotatably mounted crank case, of a plurality of engine cylinders secured to said crank case, pistons provided in said engine cylinders, pump cylinders each secured to said crank case between adjacent ones of said engine cylinders, each of said pump cylinders being connected with a source of supply of explosive gas, pistons provided in said pump cylinders, oppositely disposed inlet and exhaust ports in the engine and pump cylinders, passageways connecting the exhaust ports of the pump cylinders to the inlet ports of the engine cylinders, and a fixed crank shaft provided in said crank case and connected with all of said pistons whereby said crank case and said cylinders may be rotated. 110

3. In an engine of the class described, the combination with a rotatably mounted crank case, having a plurality of engine cylinders and a plurality of pump cylinders secured thereto, of pistons provided in each 115

of said cylinders, a fixed crank shaft, connecting rods extending between said crank shaft and each of said pistons, pipes connecting each of said pump cylinders with a 5 source of supply of explosive gases, and oppositely disposed inlet and exhaust ports in the engine and pump cylinders, passageways connecting the exhaust ports of the pump cylinders to the inlet ports of the engine cylinders. 10

4. In an engine of the class described, the combination with a rotatable crank case, of a fixed crank shaft disposed to extend through said crank case, a plurality of engine cylinders secured to said crank case, a plurality of pump cylinders each secured to said crank case between adjacent ones of said engine cylinders, pistons provided in said engine cylinders and in said pump 20 cylinders, connecting rods disposed to connect each of said pistons with said crank shaft, a carbureter, communicating means connecting said carbureter with said crank case and forming a gas chamber, pipes connecting said pump cylinders and said gas chamber, oppositely-disposed inlet and exhaust ports in the engine and pump cylinders, and passageways connecting the exhaust ports of the pump cylinders to the 25 inlet ports of the engine cylinder. 30

5. In an engine of the class described, the combination of a crank case having a plurality of engine cylinders and a plurality of pump cylinders secured thereto said 35 pump cylinders each being provided with ports that are connected with a source of supply of explosive gases and with exhaust ports, oppositely-disposed inlet and exhaust ports in the engine cylinders, passageways between the engine cylinder inlet 40 ports and the pump cylinder exhaust ports, pistons disposed to reciprocate in each of said pump cylinders each of said pistons being provided with a port near its lower end and being further provided with an angularly disposed partition whereby a charge 45 of explosive gases may be admitted above the top of said piston when it is withdrawn toward the center of said crank case and 50 which gases may be discharged through said port into one of said engine cylinders through the passageways when said piston is at the limit of its outward movement, a fixed crank shaft, and connecting rods articulating said pistons and said crank shaft. 55

6. An engine of the class described, embodying a crank case having a plurality of engine cylinders and a plurality of pump cylinders secured thereto, and hollow pistons 60 disposed in each of said pump cylinders adapted to be reciprocated therein, an inlet and outlet port in each pump cylinder, a diagonally disposed partition in each pump

piston dividing the piston chamber into inner and outer compartments substantially 65 equal in cross-sectional area, the partition extending from the inner end on one side of the piston to the outer end of the piston on the opposite side thereof, and each pump cylinder piston being further provided with 70 a port extending through its wall at the outer end into the space on the compression side of said partition.

7. In an engine of the class described, the combination with a crank case having a plurality of pump cylinders and engine cylinders secured thereto, of ports provided in said cylinders, means connecting each of said pump cylinders with one of said engine cylinders, means connecting each of said pump 80 cylinders with a source of supply of explosive gases, pistons disposed to reciprocate in said cylinders, each of the pistons in said pump cylinders being provided with a diagonal partition extending from the inner end 85 thereof to the opposite outer end and with a port adjacent to the lower end of said diagonal partition leading from the compression side thereof, whereby a charge of explosive gases may be admitted to said pump 90 cylinder above the top of said piston when said piston is at the limit of its inward movement and which gases may be discharged through said port when said piston is at the limit of its outward movement. 95

8. An internal combustion engine embodying fluid compressing cylinders provided with ports, a hollow piston disposed in each of said cylinders adapted to be reciprocated therein, each of said pistons being provided with a diagonally disposed partition extending from one side of its compression end to the opposite side of its other end to divide the hollow space therein into substantially equal compartments and each 100 being further provided with a port extending through its wall at the other end from the space on the compression of such partition. 105

9. In an engine of the class described, a plurality of communicating engine and pump cylinders, a piston in each cylinder, the pump cylinder pistons being hollow and having a compound curved partition wall 110 extending from the inner end of the piston to the opposite outer end thereof, oppositely-disposed inlet and exhaust ports in each cylinder, and an outlet port in the pump cylinder piston on the compression side adjacent the inner end thereof. 115

In witness whereof, I hereunto subscribe my name this 18th day of July A. D., 1914.

ROBERT A. BLUME.
